OSCILLATABLE AND REMOVABLE RACEWAY

Original Filed Dec. 22, 1944

UNITED STATES PATENT OFFICE

2,499,492

OSCILLATABLE AND REMOVABLE RACEWAY

Sylvester L. Gookin, Quincy, Mass., assignor to
United Shoe Machinery Corporation, Flemington, N. J., a corporation of New Jersey

Original application December 22, 1944. Serial No. 569,333. Divided and this application June 30, 1949, Serial No. 102,295

2 Claims. (Cl. 218—15.1)

1

The purpose of the present invention is to provide improvements in hoppers and raceways for supplying small articles in orderly sequence from a mass of such articles. The improved features hereinafter described are illustrated as embodied in a hopper and a raceway designed to supply eyelets in an eyeleting machine of the type set forth in United States Letters Patent No. 2,443,682, granted June 22, 1948 on an application filed in the name of Clyde L. Knott. This application is a division of application Serial No. 569,333, filed December 22, 1944.

In shoe factories, eyelets of many different sizes and styles are required for shoes of various styles, and this circumstance involves the removal of every residual unused eyelet from the raceway and hopper of an eyeleting machine whenever the latter is to be loaded with eyelets of a different size, color or style.

The raceway and hopper hereinafter described are designed to expedite the removal of residual unused eyelets and to insure their total removal despite a tendency of some of them to remain concealed or caught by the brush located in the hopper to stir the eyelets and feed them toward an emission port.

For that purpose the hopper is provided with a large opening in the bottom for discharging residual unused eyelets away from the emission port, and with a gate mounted on a hinge-pin in the manner of a downwardly opening trap-door which, when closed, contains the eyelets in the hopper. A rotary brush carried by the gate is arranged to stir the eyelets and feed some of them toward the emission port when the gate is closed, but, if rotated when the gate is open, it casts off the few residual eyelets that might otherwise remain on the gate or in the tufts of the brush. For that reason the hinge-pin is arranged to be rotated individually and the gate is provided with means for transmitting rotation from the pin to the brush not only when the gate is closed but in all positions thereof without interrupting the driving relations of the transmission elements.

Removal of unused eyelets from the raceway may be accomplished by detaching the latter and inverting it end for end. When the elements are assembled in their cooperative relation the receiving end of the raceway projects into an opening in the hopper and is movable relatively thereto, while the delivery end is supported by a movable member arranged to move it to and fro sidewise without moving the hopper. The delivery end and the movable supporting member are provided with coupling means by which

the receiving end of the raceway is maintained in its opening in the hopper.

Referring to the drawings,

Fig. 1 is a sectional elevation of a hopper, a raceway and portions of an eyeleting machine in assembled relation;

Fig. 2 is an inclined sectional plan indicated by line II—II in Fig. 1;

Fig. 3 is a sectional view indicated by line III—III in Fig. 1; and

Fig. 4 is a top plan view of the lower portion of the raceway.

The hopper 10 is mounted on and affixed to a supporting structure which may be the frame 11 of an eyelet-inserting machine of the type shown and described in the aforesaid Knott patent. The hopper has an inclined bottom wall 12 and chamber-forming walls 13 extending upwardly therefrom. A large opening 14 is provided in the bottom wall to discharge unused eyelets when it is desired to clear the hopper, but this opening is normally closed by a gate 15 mounted on a horizontal hinge-pin 16, the gate having a pair of spaced ears (Fig. 3) through which the pin extends. A torsion spring 17 normally closes the gate and thereby maintains its eyelet-supporting surface 18 in an inclined plane and in contact with the under surface of the wall 12 with enough force to sustain any load of eyelets within the capacity of the hopper. A handle 19 formed on or affixed to one of the ears of the gate provides for opening the latter against the closing force of the spring 17. When the handle is swung upwardly the lower margin of the gate swings downwardly, and the contents of the hopper will then be discharged through the opening 14. The frame 11 is provided with a baffle 20 arranged to deflect the discharged eyelets into a box, can or other receptacle (not shown). The upper margin of the gate has a cylindrical surface 21 in concentric relation to the pin 16 and in tangential relation to the under surface of the wall 12 to prevent eyelets from being caught in that region when the gate is open.

The hinge-pin 16 is journaled in the frame 11 and may be rotated without moving the gate. A pulley 22 affixed to the pin is arranged to transmit rotation from a belt 23. The gate carries a rotary assemblage comprising a brush 24, a worm-gear 25 and a shaft 26 connecting them, the brush being inside the gate and arranged to lie in the opening 14 when the gate is closed. The gear 25 is outside the gate, and the shaft extends through the gate and is journaled in it. The gear 25 cooperates with a

worm 27 to transmit rotation from the pin 16 to the brush, the worm being affixed to the pin.

When the gate is closed the brush stirs the eyelets lying on the surface 18 and feeds some of them toward the upper end of a raceway 30, but when the gate is open the brush will cast off any eyelets lodged on or between its tufts, since its rotation is not interrupted by opening the gate.

The upper end of the raceway projects into the wall 13 of the hopper that has contact with the lower margin of the gate. The opening for its reception is formed in part in the baffle portion 20 and in part in the lower surface of a block 31 mortised into the contiguous wall 13 of the hopper and constituting a movable section thereof. The baffle portion 20 provides support for the raceway without constraining it against lengthwise movement or sidewise angular movement. The block 31 and the contiguous wall 13 have mated cylindrical bearing surfaces 32 that enable the block to oscillate about its center in response to sidewise angular movement of the raceway. When the upper end of the raceway is installed as shown in Fig. 1 the supporting element 20 maintains its channel in register with the normal plane of the eyelet-supporting surface 18 of the gate.

The lower end of the raceway is supported and oscillated sidewise by an arm 33 to present eyelets to an eyelet-inserting tool (not shown). The arm 33 has a shank or stem portion 34 journaled in the frame 11 and is oscillated by a power-operated mechanism including an operating arm the hub 35 of which is affixed to the stem portion 34.

To provide an operating connection between the raceway and the arm 33, a steel ball 36 is interposed between them, the arm having a hemispherical socket 37 and the raceway having a similar socket in which the ball is seated. A semicircular spring clip 38 is provided to maintain assembled relation of these parts. One end of the clip is attached to the arm by a hinge-pin 39 and the other end is provided with a small seat to engage a depression in the raceway. When the clip is disengaged, the raceway may be re-

4
moved from the ball and then its upper end may be withdrawn from the hopper, but when the ball-and-socket elements are assembled and clipped, the ball maintains the assembled relation of the raceway and the hopper. When a loaded raceway is detached, it may be emptied by inverting it end for end, the eyelets therein will run out through the entering end of its channel which is straight and uninterrupted.

Having described my invention, what I claim as new and desire to secure by Letters Patent of the United States is:

1. In an eyeleting machine, an eyelet-hopper having an inclined eyelet-supporting surface and chamber-forming walls extending upwardly therefrom, one of said walls having an opening through which eyelets lying on said surface may gravitate therefrom, an inclined raceway the upper end of which is located in said opening, means for supporting the upper end of the raceway in register with said surface, a movable operating member arranged to support the lower end of the raceway and reciprocate it sidewise, and coupling means by which said movable member and the lower end of the raceway are connected and by which the upper end of the raceway is maintained in said opening.

2. A hopper-and-raceway assemblage for cooperating with an eyeleting machine having a reciprocating operating member, the hopper having an inclined eyelet-supporting surface and chamber-forming walls extending upwardly therefrom, one of said walls having an opening through which eyelets lying on said surface may gravitate therefrom, an inclined raceway the upper end of which is located in said opening, means for supporting said upper end in register with said inclined surface, and coupling means by which the lower end of the raceway is operatively connected to said operating member and by which the upper end of the raceway is maintained in said opening.

SYLVESTER L. GOOKIN.
